BOAT COVER

Arnold Skjelvland, Stewart Manor, N. Y.

Application December 31, 1947, Serial No. 794,866

1 Claim. (Cl. 135—6)

1

This invention relates to improvements in covers for boats and more particularly to improvements in covers for boats in storage.

Protection for the hulls of pleasure and other boats in out of season storage frequently becomes a major problem.

It is an object of this invention to provide an effective cover which may be quickly erected.

A further object is to provide a cover requiring but slight auxiliary equipment attached directly to the boat.

Still another object is to provide a cover that is readily stored in a small space when not required.

It is also an object of this invention to so form the cover that the ultimate cost is substantially low.

Other objects will become apparent in the course of the following specification.

In the attainment of these objectives, the cover is made of any suitable water resistant or water repellent flexible material supported by a longitudinal stay inserted in the apexes of collapsible supports transversely mounted along the deck of the boat. The collapsible supports comprise angular members hinged at the apex in such a way that when the members are extended there is a substantial aperture at the apex utilized for the support of the stay. At the base of each collapsible support is a horizontal brace hinged in the center and to the angular members which prevents any movement of the members of the support beyond that required at the intended point of erection on the ship's deck. Constructed in the manner shown, the collapsible supports not only provide adequate support for the cover but take little storage space when not in use.

The invention will appear more clearly when taken in connection with the accompanying drawing showing by way of example a preferred embodiment of the inventive idea.

In the drawings:

Figure 1 is a view in perspective of the collapsible supports erected transversely on the boat with the cover removed and constructed in accordance with the principles of this invention.

Figure 2 is a view in perspective of the cover inserted over the supports.

Figure 3 is a fragmentary view of the fore end of the boat provided with a turnbuckle for tightening the stay, and enlarged.

Figure 4 is a fragmentary view of the aft end of the boat provided with a hook and eye to secure the opposite end of the stay, also enlarged.

Figure 5 is an enlarged perspective view of the collapsible support.

2

Figure 6 is a fragmentary view of the collapsible support showing the manner of attaching the hinged joints at the apexes, likewise enlarged.

Referring now in greater detail to the drawings in which like reference numerals indicate like parts, reference numeral 10 indicates the boat, 11 the flexible cover, 12 the collapsible supports, and 13 the stay.

The collapsible supports 12 (Fig. 1) are formed of the angular members 14 and the horizontal braces 15. The members 14 are connected at the apex by the hinge 18 attached on the inside of the members. With the hinge 18 attached as shown in Figures 5 and 6, the aperture 19 is formed between the hinged ends of the members 14 in other than a straight angle position. The horizontal brace 15 of the support 12 may be folded and is hingedly attached to the members 14 as shown in Figure 5. Here, it will be noted, that as the angular members 14 are pushed apart, brace parts 20 and 21 of the brace 15 tend to approach the limit of a straight angle.

With the hinges 22, 23, and 24 attached as shown, the brace parts 20 and 21 are locked from moving together in the straight angle position because of the abutting ends 24 and 25 of the parts 20 and 21, respectively, thereby providing a substantial support for the stay 13 as subsequently shown as well as a means for collapsing into a small unit when not in use.

In the erected position (Fig. 1), each collapsible support 12 has a base width substantially equal to the width of the boat at the point of erection and the ends of the angular members 14 are cut at the proper angle for erection along the deck of the boat at the sides. Obviously, where boats are made in standard sizes, the supports 12 may be also in standard size. Moreover, the number of supports 12 required may vary from boat to boat.

Through the apertures 19 (Figs. 5 and 6), at the top of the angular members 14, the stay 13 is passed for longitudinal attachment at the fore and aft end of the boat 10. At the aft end, the hook 26 is attached to the end of the stay 13 to co-act with the eye 27 attached to the stern as shown in Figure 4. At the fore end, the eye 28 (Fig. 3) is attached at the bow to co-act with the turnbuckle 29 attached to the fore end of the stay 13. By tightening the turnbuckle 29, the stay 13 is drawn taut over the top apertures 19 of the supports 12 thoroughly securing the supports 12 to the top surface portion of the deck of the boat 10.

It will be noted that the ends of the brace parts 20 and 21 of the brace 15 are hingedly connected to the angular members 14 of the support 12 sub-

stantially above the free ends of the members 14 which enables the support 12 to be inserted directly over the perpendicular member or gunwale 39 (Fig. 1) around the well 31 of the boat 10.

It is apparent that the specific illustration shown above has been given by way of illustration and not by way of limitation, and that the structures above described are subject to wide variation and modification without departing from the scope or intent of the invention, all of which variations and modifications are to be included within the scope of the present invention.

What is claimed is:

A boat cover comprising at least one collapsible support, the support comprising two angular members hingedly connected at one end, a collapsible brace hingedly disposed between the angular members intermediate the ends thereof, the brace comprising two hingedly connected members collapsible in the direction of the hinged ends

5 of the angular members, a flexible stay adapted to be connected to the opposite ends of the boat, means supporting the stay by the angular members, and a flexible cover supported over the stay and the collapsible support and adapted to be removably secured to the sides of the boat.

ARNOLD SKJELVELAND.
